UNITED STATES PATENT OFFICE.

AARON WEISBERG, OF BROOKLYN, NEW YORK.

GAME AND TOY.

Application filed July 19, 1924, Serial No. 726,896. Renewed November 14, 1925.

The invention relates to an amusement apparatus and resides more particularly in an apparatus comprising an elongated upwardly and rearwardly inclined table bearing a series 5 of corresponding pairs of pivoted wings or doors arranged in a straight row, with the wings or doors of each pair converging rearwardly and substantially meeting at their free edges, and a series of marbles to be used 10 by the players or users of the apparatus and shot, with the thumb as usual, at the converging edges of the first pair of wings or doors and with the purpose that the marble should force its way as far through the row 15 of wings as the skill of the player might admit, the pairs of wings or doors, one after another, opening outwardly under the impact of the marble and automatically closing behind it. When the marble has spent its 20 force in traveling through the pairs of wings or doors, it will be deflected laterally by the then closed wings or doors just behind it and pass into a pocket or the like and become arrested. The row of wings or doors will 25 preferably contain, say, twelve pairs thereof, and one prime object of the player will be to shoot the marble with such directness and force that it will open and pass between all 30 of the pairs of wings or doors and strike a target or bell arranged on the upper rear portion of the table. The players will receive different counts according as the marbles shot by them travel different distances 35 through the row of wings or doors.

The invention will be readily understood from the detailed description hereinafter presented, reference being had to the accompanying drawings, in which:

Fig. 1 is a side elevation, partly broken away and partly in section, of an apparatus embodying my invention;

Fig. 2 is a plan view of the same;

Fig. 3 is a plan view, partly broken away and partly in section, of the same, a marble being shown as having completed a shot and the dotted line indicating the lateral deflection of the marble toward one of the pockets to arrest the same;

Fig. 4 is a vertical longitudinal section, 50 through a portion of the same, taken on the dotted line 4-4 of Fig. 3;

Fig. 5 is a vertical transverse section, 55 through the same, taken on the dotted line 5-5 of Fig. 3 and illustrating the marble as having been caught in one of the side pockets;

Fig. 6 is a perspective view of one of the wings or doors detached from the apparatus, and

Fig. 7 is a vertical transverse section 60 through a portion of the apparatus, taken on the dotted line 7-7 of Fig. 3.

In the drawings, 10 designates an elongated upwardly and rearwardly inclined table or game board having an upwardly 65 extending border rim or flange 11 and being supported at its rear portion by a foldable easel-bracket 12, while at its lower front end said table may rest directly on any base on which the apparatus may be placed. I 70 preferably form the table 10 of sheet metal and give the same an attractive finish.

Upon the table 10 is arranged a straight 75 row of corresponding pairs of pivoted or hinged wings or doors 13, 14 respectively, these wings or doors preferably being of sheet metal and, in each pair, extending rearwardly on inclined converging lines toward each other and substantially meeting at their free edges, said wings or doors of 80 each pair being normally held in this inclined relation to each other by stops 15, 16 hereinafter definitely described. The pairs of wings or doors 13, 14 are correspondingly spaced apart and any desired number of 85 these pairs of doors may be applied upon the table 10, although my experience is that twelve pairs of the doors provide a satisfactory apparatus.

The wings or doors 13, 14 stand at right 90 angles to the table 10 and are confined between said table and an upper skeleton plate or frame 17, which is preferably of sheet metal and connected with and suitably spaced from the table 10 by means of rivet rods 18. The frame 17 is of skeleton formation in its top so that the players may observe the action of the marbles and doors during the use of the apparatus. The frame 17 is of box formation at its edges, particularly at its side edges, the metal of said frame being bent downwardly, as at 19, and then inwardly, as at 20, to afford smooth outer edges at 19 and an underlying border flange at 20, which I make use of in pivot- 100 ing or hinging the doors 13, 14.

The doors 13, 14 are somewhat elongated or oblong in outline and are all alike in respect to the details of their construction. Each door is a flat sheet of metal and is 110 formed on the upper and lower ends of its outer edge with lower and upper pivot pro-

jections 21, 22, respectively, which are adapted to small holes 23 formed in the table 10 and corresponding holes 24 formed in the aforesaid flange 20. The doors are loosely sustained between the flange 20 and table 10 so that they may have a free swinging movement, the projections 21, 22 and their bearing holes 23, 24 serving to pivotally mount or hinge said doors. The lower edges of the doors 13, 14 are free of the table 10 except at a small portion 25 thereof adjacent to the hinged edge of the door, this detail of construction being to avoid unnecessary friction between the lower edge of the door and the adjacent surface of the table 10.

The table 10 at the forward side of each door and adjacent to the outer edge thereof, has a lug to serve as a stop 15 for arresting the door in its normal rearwardly and inwardly inclined position, without at all interfering with the doors being opened rearwardly in a direction from each other under the impact of a marble shot against them. A stop 15 is provided for the lower edge of each of the doors 13, 14, and hence said doors in pairs become arrested and normally held in their rearwardly converging relation shown, with their free edges close together but preferably not touching each other.

In addition to the stops 15 for the lower edges of the doors 13, 14, I preferably provide the upper stops 16 for the upper edges 35 of the doors to coact with the stops 15 in arresting the pairs of doors in their normal converging relation. The stops 16 are formed by the forward edges of notches 27 cut in the flanges 20 adjacent to the bearings 40 24 for the upper pivot projections 22 on the doors. In forming the projections 22 I recess the upper edge of each door, at 28, and this leaves the upper edge of the door in position to engage the stop-edge 16 of the notch 45 27 in the closed position of the door. The notches 27 are of such shape as not to interfere with the opening of the doors to the limit allowed by the edges 26 of said notches.

In assembling the parts of the apparatus 50 I first position all of the doors 13, 14 on the table 10 and then apply the upper frame 17 over the doors, with the bearing holes 24 in the flanges 20 lowered over the pivot projections 22 on the doors, and I thereupon secure the frame 17 in position by means of the rivet rods 18.

Upon the upper end portion of the table 10 I preferably secure a bell or gong 28, which will be struck by a marble succeeding in passing through all of the doors on a single shot. At the side portions of the table 10 I provide openings or pockets 29 therein to catch marbles deflected laterally by the intermediate doors or by the first pair of doors, as the case may be, these open-

ings or pockets 29 serving to catch and retain the marbles 30.

On the top of the frame 17 are arranged suitable score numbers, as shown in Fig. 2, denoting the respective values of the shots 70 made when the marbles become arrested adjacent to said numbers.

By reason of the fact that the doors 13, 14 are at a right angle to the face of the table 10, the said doors take an inclined position 75 from the vertical when the table 10 is tilted to its operative position and supported on the bracket 12, as shown in Fig. 1, and in this position of the doors 13, 14 said doors have a natural tendency to close forwardly 80 toward each other and against the stops 15, 16. The tendency of the doors 13, 14 to move to their initial position results in the doors closing automatically after they have been opened rearwardly by the impact of a 85 marble 30.

I do not deem it necessary to employ both the lower stops 15 and upper stops 16 for the doors 13, 14, because either set of stops 90 would serve to arrest the doors in their normal position, but for completeness of manufacture I prefer to use both sets of stops.

The upper frame 17 may take any suitable outline, but the outline shown in Fig. 2 is one well adapted for the purpose and exposes the operation of the doors 13, 14 and marble 30 when the apparatus is in use. At the longitudinal center of the frame 17 is an integral bar which crosses the junctions of the free edges of the doors 13, 14, 100 and this bar affords a convenient space for the numerals indicating the values of the shots and also serves to prevent a marble passing through the sets of doors from being deflected upwardly from the apparatus. The frame 17 serves under all circumstances for confining a marble 30 when shot at the doors against being deflected upwardly either due to a defective shot or other cause. 105

The apparatus may be used by one person 110 for his own amusement or by several persons playing in competition with one another. A player will rest his hand on the lower forward flat portion of the table 10 and shoot a marble at the free edges of the first 115 pair of doors 13, 14, and the impact of the marble will open said doors and the marble will probably pass inwardly between a number of the succeeding doors and finally lose 120 its force and be deflected laterally by the pair of doors closing behind it, the marble finally reaching one of the pockets 29. After 125 considerable practice, a player may shoot the marble between all of the doors of the set and strike the gong 28, this giving him the highest score mark possible for a single shot. Some tact is required to so shoot the marble that it will only pass between the first pair of doors 13, 14, and hence on the scoring a player will receive fifty marks 130

for a shot of this kind. The values of the various shots made are indicated at the top of the frame 17, as shown in Fig. 2, but these value markings may vary within the 5 judgment of the manufacturer.

I do not confine my invention to all of the details of form and construction hereinbefore specifically described, since I am aware that many of these may be varied 10 without departure from the spirit of my invention and within the scope of the appended claims.

I contemplate constructing the apparatus hereinbefore described on a larger scale than 15 that indicated in the drawings and to utilize the same with a ball or the like which will be larger than a marble, the ball instead of being technically shot at the front pair of wings or doors being pitched or slid or thrown against said doors. When the 20 apparatus is constructed on the larger scale indicated there will be no change therein, except as to dimensions. I mention this so that it will be understood that I do not limit 25 my invention wholly to the use of what is technically known as a marble, and wherever I have used the word "marble" in my specification and claims I desire to have it understood that I include in that expression any 30 marble or ball to be projected by hand against the front pair of doors for carrying out the operation hereinbefore described in referring to marbles.

What I claim as my invention and desire 35 to secure by Letters Patent, is:

1. A game apparatus of the character described comprising a table having thereon a straight row of spaced-apart independent pairs of doors hinged at their outer edges and substantially coming together at their 40 free edges and adapted to be opened rearwardly and in a direction from each other and to close automatically, the doors of each pair normally standing on rearwardly converging lines, a frame applied closely over the row of doors and open at its sides and 45 ends, and a marble to be shot at the free edges of the front pair of doors and by its impact to open and pass said doors and also open and pass successive pairs of doors until its force has been spent.

2. A game apparatus as claimed in claim 50 1, in which the doors of each pair normally stand on rearwardly converging lines and are adapted to deflect a spent marble laterally from the row of doors to a side portion of the table.

3. A game apparatus as claimed in claim 55 1, in which the doors of each pair normally stand on rearwardly converging lines and are adapted to deflect a spent marble laterally from the row of doors and in which the table at the sides of the successive pairs of doors is provided with pockets to receive the deflected marble at the point at which it ceased to operate.

4. A game apparatus as claimed in claim 60 1, in which the table has means for supporting it in an upwardly and rearwardly in-

clined position, in which said doors stand on a plane at right angles to the face of the table, in which the doors of each pair normally stand on rearwardly converging lines, and in which the table is provided at each 70 side of the row of doors with pockets to receive a spent marble deflected laterally by the last doors it passed through.

5. A game apparatus as claimed in claim 75 1, in which the table is adapted to be supported in an upwardly and rearwardly inclined position, in which the doors of each pair normally stand on rearwardly converging lines and in which a skeleton frame is applied closely over the row of doors and 80 is open at its sides and ends.

6. A game apparatus as claimed in claim 85 1, in which the table is adapted to be supported in an upwardly and rearwardly inclined position, in which the doors of each pair normally stand on rearwardly converging lines, in which a frame is applied closely over the row of doors and is open at its sides and ends, in which the table has pockets at the sides of the row of doors to 90 receive spent marbles and in which at the upper end of the table is provided a gong or the like to be engaged by a marble which has passed through the entire row of doors.

7. A game apparatus of the character described comprising a table having thereon a straight row of spaced-apart independent pairs of doors hinged at their outer edges and substantially coming together at their 95 free edges and adapted to be opened rearwardly and in a direction from each other and to close automatically, the doors of each pair normally standing on rearwardly converging lines, a frame applied closely over the row of doors and open at its sides and 100 ends, and a marble to be shot at the free edges of the front pair of doors and by its impact to open and pass said doors and also open and pass successive pairs of doors until its force has been spent, the means hinging 105 said doors being pivot projections formed on the upper and lower ends of the outer edges of said doors and bearing holes for said projections formed in said frame and 110 table.

8. A game apparatus of the character described comprising a table having thereon a straight row of spaced-apart independent pairs of doors hinged at their outer edges and substantially coming together at their 120 free edges and adapted to be opened rearwardly and in a direction from each other and to close automatically, the doors of each pair normally standing on rearwardly converging lines, a frame applied closely over the row of doors and open at its sides and 125 ends, and a marble to be shot at the free edges of the front pair of doors and by its impact to open and pass said doors and also open and pass successive pairs of doors un- 130

til its force has been spent, said frame having along its side edges underlying flanges formed with angular notches whose forward edges serve as stops for arresting the doors in their normal closed position and whose rear edges serve as stops for arresting the doors against undue opening movement, and the means hinging said doors being pivot projections formed on the upper and lower ends of the outer edges of the doors and bearing holes formed in said flanges at said notches for the upper projections and corresponding holes formed in said table for the lower projections.

15 9. A game apparatus as claimed in claim 1, in which the table is adapted to be sup-

ported in an upwardly and rearwardly inclined position, in which the doors of each pair normally stand on rearwardly converging lines, in which a skeleton frame is closely applied over the row of doors and is open at its sides and ends, in which pockets are provided along the sides of the row of doors to receive spent marbles, in which stops are provided to arrest the doors in their normal closed position, and in which stops are provided to arrest the doors against undue opening movement.

Signed at New York city, in the county of New York and State of New York, this 18th day of July, A. D. 1924.

AARON WEISBERG.
